DISPLAY PACKAGE FOR A LIPSTICK

Morton Edell, Newark, N.J.
(2345 Vaux Hall Road, Union, N.J.)

Filed Aug. 6, 1962, Ser. No. 71,179

Term of patent 14 years

(Cl. D58—2)

FIG. 1 is a perspective view of a display package for a lipstick showing my new design;

FIG. 2 is a front elevational view thereof;

FIG. 3 is a side elevational view thereof;

FIG. 4 is a partial, exploded view thereof; and

FIG. 5 is a bottom view thereof.

The characteristic features of my design reside in the combination of a flat card having a blister portion at its base which encloses one-half the lipstick tube with a bead near the open end, said end portion which tapers downwardly and flares outwardly.

I claim:

The ornamental design for a display package for a lipstick, substantially as shown and described.
